(57) **CLAIM**

The ornamental design for a “a clip of a mobile phone,” as shown and described.

DESCRIPTION

FIG. 1 is the perspective view of a “a clip of a mobile phone” showing my new design;

FIG. 2 is the front view thereof;

FIG. 3 is the rear view thereof;

FIG. 4 is the left side view thereof;

FIG. 5 is the right side view thereof;

FIG. 6 is the top view thereof;

FIG. 7 is the bottom view thereof; and,

FIG. 8 is the perspective view showing the practical usage thereof.

The broken line showing of environment in FIG. 8 is for illustrative purposes only and forms no part of the claimed design.
